UNITED STATES PATENT OFFICE.

EDWARD P. ALSTED, OF TRUESDELL, WISCONSIN.

ATTRITION-MILL.

1,255,845.

Specification of Letters Patent. Patented Feb. 12, 1918.

Application filed September 13, 1916. Serial No. 119,829.

To all whom it may concern:

Be it known that I, EDWARD P. ALSTED, a citizen of the United States, and resident of Truesdell, in the county of Kenosha and State of Wisconsin, have invented new and useful Improvements in Attrition-Mills, of which the following is a description, reference being had to the accompanying drawings, which are a part of this specification.

10. This invention relates to improvements in attrition mills and more particularly to mills in which the material is reduced between opposite disks rotated in opposite directions and provided on their working faces with plates, not in contact with each other, the plates being provided with ribs and pockets therebetween to reduce the material by attrition.

One of the objects of the present invention is to provide an attrition mill in which the material being reduced between the plates is evenly distributed throughout the entire surface of the plates thereby preventing the material from working outwardly, centrifugally, without being reduced, thereby preventing excessive and uneven wear of the grinding surfaces at different points.

A further object of the invention is to provide an attrition mill in which the pockets or recesses formed in said plates are so positioned with relation to the pockets or recesses formed in the opposing disk that material may freely pass radially from one series of pockets to another.

35. A further object of the invention is to provide an attrition mill having plates with some of their teeth undercut to form a better cutting edge and other teeth with beveled side portions to reinforce the same and eliminate the possibility of breakage due to particles of foreign matter passing between the plates.

40. A further object of the invention is to provide an attrition mill having plates with segmental eccentric ribs which differ in position with relation to opposite plates of a pair to form a shearing cut between said segmental ribs and also to form a limited space for the outward movement of the material being reduced.

45. A further object of the invention is to provide an attrition mill which is of simple construction, is strong and durable and is well adapted for the purpose described.

50. A further object of the invention is to

provide an attrition mill having plates provided with ribs shaped to form a shearing cut therebetween and to also form plates which in a degree are self sharpening.

With the above and other objects in view the invention consists of the improved attrition mill and its parts and combinations as set forth in the claims, and all equivalents thereof:

55. In the accompanying drawing in which the same reference characters indicate the same parts in all of the views:

Figure 1 is a front view of a portion of one of the grinding plates of the improved attrition mill;

Fig. 2 is a similar view of a part of the other plate of the pair of plates;

Fig. 3 is an enlarged face view of one of the plate sections;

Fig. 4 is a sectional detail view thereof taken on line 4-4 of Fig. 3;

Fig. 5 is a sectional detail view thereof taken on line 5-5 of Fig. 3;

Fig. 6 is a transverse sectional view of two plates of a pair taken on line 6-6 of Fig. 3; and

Fig. 7 is a diagrammatic view of one of the radial ribs of each plate showing line of engagement therebetween.

Referring to the drawing the numeral 8 indicates one of a plurality of segmental grinding plates which are adapted to be fastened to the opposing heads or disks (not shown) of the attrition mill by means of screws 9 passing through openings 10 provided in said plates and threaded to the disks. The segmental plates are provided with outer radial ribs 11, inner radial ribs 12, an outer concentric rib 13 and inner segmental eccentric ribs 14 and 14' forming recesses or pockets 15 and 16. The inner concentric edges 17 of the plates are beveled off to more freely admit the material to be reduced into the pockets between the plates, and the radial ribs start or project from the flat portion of the plates at and near the line where the beveled edge merges with said flat portion, each alternate radial rib being somewhat shorter than the adjacent radial ribs.

While the radial ribs 12 extend in substantially radial lines from the axis of the disks the cutting or working edges 18 of said ribs extend in tangential lines of different angles from a small circle concentric with

said axis. The inner ends 19 of said portions of said ribs are comparatively narrow and diverge outwardly to a greater degree than radially to provide a shearing cut of 5 the line of engagement which travels inwardly as shown in Fig. 7 of the drawing. The ribs 12 are also undercut as indicated by the numeral 20 to form sharper cutting edges and which cutting edges will 10 remain in better cutting shape during the wear of said ribs.

The radial ribs 11 have their cutting edges 21 on their opposite sides substantially parallel with relation to each other and tangentially with relation to a small circle concentric to the axis of the plates and whose diameter approximately equals the width of the ribs to form a slight shearing cut, the line of engagement of which travels outwardly. The ribs 11 increase in width toward the base of the plates as indicated by the numeral 22 to reinforce and increase 20 the strength of the ribs so that they can better withstand engagement with particles 25 of metal or other foreign matter which may inadvertently get in the grain being reduced. The foreign matter thus engaged will be cut or broken into such small particles by the reinforced ribs that no damage 30 will be done to the outer radial ribs of less strength. The inner side edge 26 of the eccentric ribs 14 and 14' bevels inwardly toward the axis of the plates to also reinforce 35 these ribs for the same purpose just before mentioned.

The material being reduced between the attrition faces of the plates is fed to said plates from the inner portion thereof, and is moved outwardly therefrom by centrifugal 40 force.

It will be noticed that the eccentric ribs 14 or 14' of the segmental plates extend in a curve of larger diameter than that portion of the plate upon which the rib is positioned, 45 or in other words the rib is eccentric to the path of travel of the segment, and when the plates are assembled on the disks or heads of the attrition mill the ends of the eccentric ribs meet and form a hexagonal shaped 50 rib with corners 23 and curved sides 24. The hexagon shaped rib is positioned concentric to the axis of the disks and one of the ribs is of slightly larger diameter than the other, and when the opposing plates are 55 oppositely rotated the corners of the smaller rib will overlap the portions of the larger rib and form a shearing cut and at the same time other portions of the ribs will be spaced from each other radially to form communicating passageways as indicated by the 60 numeral 25 in Fig. 6 to permit some of the material to freely pass from the inner pockets to the outer pockets and thus evenly distribute the material being reduced between 65 the plates.

Both side edges of the radial ribs are similar in shape so that when the edges on one side are worn the disks may be rotated in the opposite direction and the same results be obtained.

70

From the foregoing description it will be seen that the attrition mill is of very simple construction and that the material being reduced is spread evenly between the grinding plates and that the wear thereof is thus 75 evenly distributed throughout all of the working portions of the plates.

What I claim as my invention is:

1. An attrition mill, comprising rotatable opposite plates provided with radial ribs, the material engaging edges of the ribs of opposite plates being undercut and converging toward the axis of said plates for a portion of their length and being parallel to each other at other portions of their length to advance the line of cutting engagement of said ribs toward the periphery of the said plates for a portion of the length of said ribs and toward the axis of said plates along other portions of said ribs. 80

2. An attrition mill, comprising rotatable opposite plates provided with radial and eccentric transverse ribs forming pockets therebetween, the material engaging edges of the radial ribs being partly undercut and converging toward the axis of said plates for a portion of their length and being parallel to each other at other portions of their length to advance the line of cutting engagement of said ribs toward the 85 periphery of said plates for a portion of the length of said ribs and toward the axis of said plates along other portions of said ribs, portions of said radial ribs being beveled toward the plates to reinforce their side edge 90 portions, said transverse ribs of opposite plates during rotation partly overlapping each other to permit passage of material from pockets inclosed within the transverse rib to pockets outside of said rib. 95

3. A grinding plate for attrition mills, comprising a segmental plate provided with radial ribs, the material reducing edges of adjacent ribs being undercut and diverging from each other for a portion of their 100 lengths then extending in parallel lines for a certain distance, and a beveled rib extending transversely across the radial ribs in a line eccentric to the axis of said plate. 105

4. A grinding plate for attrition mills, comprising a segmental plate having radial and transverse ribs, outer portions of the radial ribs being undercut and the material engaging edges of said undercut portions converging toward each other toward the 110 axis of the plate for a portion of their length and parallel to each other with respect to inner portions, said inner parallel portions being beveled, the outer transverse rib being concentric with relation to the axis of 115

110

120

130

the plate and the inner transverse rib being eccentric with respect to said axis.

5. A grinding plate for attrition mills, comprising a segmental plate having radial and transverse ribs, the inner cutting edge portions of the radial ribs being parallel and beveled to initially engage the ma-

terial and the outer cutting edge portions of said ribs for finally engaging the material being undercut and converging toward 10 each other.

In testimony whereof, I affix my signature.

EDWARD P. ALSTED.
